UNITED STATES PATENT OFFICE.

EDOUARD BARDET, OF NEW YORK, N. Y.

SAFETY-RAZOR-BLADE HOLDER.

Application filed May 18, 1926. Serial No. 109,958.

This invention relates to safety razor blade holders of a character adapted for use in connection with the stropping of blades of various styles and makes.

5 One object of the invention is to provide a holder for different types of razor blades which is simple in character, efficient in operation, can be cheaply and readily manufactured with a minimum of parts and 10 labor, and which, by reason of its extreme simplicity, affords a construction that enables a blade to be inserted and sharpened without the usual tedious and complicated methods of the prior art holders.

15 Other and very important features of the invention are the blade supporting members for holding a blade in position in the holder, and the cooperating means at the opposite ends of the handle members for maintaining said handle members in perfect 20 alignment when in closed position. The particular cooperating means at the opposite ends of the handle members afford rigidity of the holder and blade in the position of use.

Moreover, due to the simplicity of the construction of the holder, it requires but a very simple and quick operation to insert a blade of the desired type therein and to 25 perform whatever stropping operation is necessary within a minimum of time.

In the drawing:

Figure 1 is a perspective view of the holder of this invention shown with the handle members closed together in operative relation, there being shown a razor blade in 30 position therebetween;

Figure 2 is a perspective view of the holder of Figure 1 shown with the handle members in their open or out-of-use position;

Figure 3 is a sectional view taken substantially along the line 3—3 of Figure 1, showing a blade of the type provided with an 45 enlarged permanent back, held in position between the closed handle members of the holder;

Figure 4 is a detailed perspective view of the blade supporting member provided with 50 rigid studs adapted for use with a blade of the character illustrated in dotted lines;

Figure 5 is a sectional view of the holder with the blade supporting member and blade of Figure 4 shown in position between the 55 closed handle members, and

Figure 6 is a detailed perspective view of

a clip member employed with a particular type of razor blade, the blade being shown in dotted lines.

Referring more particularly to the drawings, wherein like numerals indicate similar parts in the several views, 10 and 11 indicate respectively the handle members of the holder of this invention.

The handle members 10 and 11 are cut 65 away at the blade receiving sections of their length as indicated at 10' and 11' respectively, to form, preferably, a diamond-shaped configuration in cross section as illustrated in Figures 3 and 5.

The handle member 10 is provided in its inner face with a plain or uninterrupted rectangular recess 12 and the handle member 11 is provided with a similar recess 13. The opposed faces of the handle members 70 are thus provided with recesses which are adapted to cooperate and to be in exact alignment when the handles are in their closed position, as illustrated in Figure 1, to receive and support a blade and holder to 75 be described hereinafter.

The handle member 10 is provided at one end with an integral longitudinally extending lug or projection 14, which has a portion 14' depending therefrom on its inner 80 face for a purpose to be hereinafter described, and at its inner end there is formed a transverse slot 15.

The handle member 11 is bifurcated at one end as shown at 16, thereby providing 85 projections or shoulders 17 and 18 which cooperate with the longitudinally extending lug or projection 14 of the handle member 10. It is to be noted that the shoulders 17 and 18 are rounded off at their lower ends 90 as at 17' and 18' respectively, to allow the squared inner end of the handle member 10 to pass them freely when it is moved into engagement with the other handle member 11, and yet afford a tight and substantially 95 close fit to prevent relative movement of the two members at their inner ends.

A pintle 19 is employed to pivotally connect the handle members together, and it will be noted that this pintle extends 100 through aligned perforations formed in the projecting lug 14 of the handle member 10 and the projections or shoulders 17 and 18 on the handle member 11.

At the opposite end of the handle member 11 there is provided a depending lug 20, 110 preferably centrally arranged with respect

to the end of the handle member, which lug is adapted to engage in the slot 15 formed in the handle member 10, thereby maintaining the outer ends of the members against relative movement when closed.

It will be seen that by reason of the provision of the elongated longitudinally projecting lug 14 of the handle member 10 of which engages the bifurcated portion 16 of the handle member 11, together with the co-operation between the centrally disposed and depending lug 20 and the transverse slot 15 of the handle members 11 and 10 respectively, a very rigid and immovable construction is effected when the handle members are in their closed position as illustrated in Figure 1.

That is to say, that, by reason of the co-operation of the parts 14, 16, 15 and 20, the handle members are maintained in perfect alignment in closed position.

In Figure 4 of the drawings there is illustrated one of the removable blade supporting members or holders in the form of a flat plate, preferably metal, having a base portion 21 and integral rigid studs 22, 22, standing therefrom.

The dimensions of the blade supporting member, that is to say the base plate 21, are such as to allow it to fit snugly within either of the recesses 12 and 13, although the fit is such as to allow its ready removal from the recess.

It will be observed that when the supporting member 21 is in position within one of the recesses, and the opposite handle member is brought into closed position with respect to the handle carrying the blade supporting member, the studs 22 project into the opposing recess. It will be noted that the top surface of the base plate 21 is, preferably, flush with the inner face of the handle member when the blade supporting member is in position within either of the recesses 12 or 13.

The blade 23 shown in dotted lines, Figure 4, is provided with perforations 24 which receive the studs 22 and maintain the blade in engagement with the base plate or blade supporting member 21.

When it is desired to sharpen a blade of the Gillette type such as that illustrated in dotted lines in Figure 4, it is merely necessary to insert a finger nail in either one or both of the notches 25 (Figure 1) provided in the opposing faces at the outer end of each handle member, to separate the handle members 10 and 11. Thereafter, the blade supporting member 21 is positioned in either of the recesses 12 or 13 and the blade of the type shown in Figure 4 is placed in position upon the member 21 with the studs 22 engaging in the recesses 24. The handle member opposite that in which the blade supporting member 21 is held, is then moved

about its pivot point or pintle 19 and the two handle members brought into intimate contact, that is to say, to their closed position as illustrated in Figure 1. It will be readily seen that the depending lug 20 on the handle member 11 will then engage in the transverse slot 15 formed in the inner end of the handle member 10, thereby maintaining the two members in perfect alignment.

While the cooperating parts 15 and 20, arranged at the outer ends of the handle members 10 and 11, respectively, are serving their purpose of maintaining those ends in perfect alignment, the longitudinally extending lug 14, arranged at the inner end of the handle member 10, by its cooperation with and engagement in the bifurcated inner end between the shoulders 17 and 18 of the handle member 11, serves to hold the inner ends of the two handle members in substantially rigid engagement and perfect alignment.

My reason of the fact that the handle members 10 and 11 are cut away at 10' and 11', respectively to provide the blade receiving sections of the handle members with a configuration substantially diamond-shaped in cross section, the sharpened edges of the Gillette type blade will extend beyond the edges of the handle members to enable each edge of the blade to be brought into engagement with a strop to allow an easy stropping operation.

When it is desired to sharpen a blade, of the character indicated at 26 (Figure 3), which blade is provided with a permanent reinforcing portion or back 27, such for example as the Ever-Ready or Gem types of blade, the blade supporting member 21 is not used.

In order to hold the blade of Figure 3 in position it is merely necessary to rest its reinforcing portion or back 27 in either of the recesses 12 and 13 and move the handle members to their closed position, as previously described.

In the event it is desirable to sharpen a blade of the Auto-Strop type, such as that illustrated in dotted lines at 28, (Figure 6) it is merely necessary to employ a clip or blade holder of the character indicated at 29, in Figure 6, and apply such holder to the upper or unsharpened edge of the blade 28.

The clip or blade holder 29, is formed, preferably, from a blank of sheet metal folded over to present a configuration which is substantially U-shaped in cross section with its lower edges flared outwardly as indicated at 30. By so constructing the clip, it may be readily applied to the upper edge of the blade, and due to its resiliency, will form a snug fit thereon.

When employing a clip or blade holder of the type shown at 29, likewise the blade supporting member 21 of Figure 4 is not used, the clip 29 being adapted to be inserted into

either one of the recesses 12 and 13 in a manner similar to that in which the blade 26, having the permanent back 27, (Figure 3), is applied to the holder.

- 5 The depth of the recesses 12 and 13 is such as to provide, when they are brought together into cooperative relation, a space merely a fraction larger than the width of either of the blade supporting members 21 and 29 or, of 10 a size approximately equivalent to the thickness of the supporting or reinforcing back member 27 of the blade 26.

By so proportioning the recesses 12 and 13 it will be readily seen that when either of 15 the blades or blade supporting members are in position in the holder, there is absolutely no chance for any relative movement between such blades, blade supporting members, and the handle members of the holder 20 of this invention.

The application of the Gillette type blade and its particular supporting member to the holder of this invention is probably best illustrated in the sectional view, Figure 5.

25 The handle members may be made of metal or other suitable material by casting or in any other suitable manner. These handle members may also be formed by stamping them out of sheet metal.

30 Applicant does not wish to be restricted to the materials employed in making the holder of this invention nor the method of producing such holder.

While the several parts of the holder

have been defined in their preferred relationship, nevertheless a reversal of parts may be used within the purview of this invention.

The holder of this invention, one embodiment of which is illustrated in the accompanying drawing, has been developed to overcome the objectionable and impracticable devices of the prior art.

I claim:

A holder for safety razor blades having 45 in combination a pair of coacting handle members having at one end projections hingedly connected together and extending vertically to prevent endwise shifting of the handle members, one of said handle members 50 at its opposite end having a depending lug adapted to engage a complementary slot in the adjacent end of the other handle member so as to coact with said projections for preventing shifting of the handle members 55 when in the closed position, the inner surface of each of said members having oppositely disposed longitudinal recesses, and a removable blade holder adapted to fit and be positively held in said longitudinal recesses, said blade holder arranged to prevent endwise as well as lateral movement of the handle members when the parts are in their 60 closed position.

In testimony whereof I have hereunto set 65 my hand.

EDOUARD BARDET.
